US00D558499S

(12) **United States Design Patent** (10) **Patent No.:** **US D558,499 S**
(45) **Date of Patent:** **** Jan. 1, 2008**

(54) **PILLOW**

(75) Inventor: **Kirsten Maarbjerg**, Odense C (DK)

(73) Assignee: **Tempur World, LLC**, Lexington, KY (US)

(**) Term: **14 Years**

(21) Appl. No.: **29/264,950**

(22) Filed: **Aug. 22, 2006**

D463,701 S * 10/2002 Borcherding et al. D6/601

FIG. 1 is a perspective view of a pillow constructed in accordance with an embodiment of the present invention;

FIG. 2 is a top view of the pillow shown in FIG. 1;

FIG. 3 is a bottom view of the pillow shown in FIGS. 1 and 2;

FIG. 4 is a front view of the pillow shown in FIGS. 1–3;

FIG. 5 is a rear view of the pillow shown in FIGS. 1–4;

FIG. 6 is a left side view of the pillow shown in FIGS. 1–5;

FIG. 7 is a right side view of the pillow shown in FIGS. 1–6;

FIG. 8 is a perspective view of an alternative embodiment of the pillow according to the present invention;

FIG. 9 is a top view of the pillow shown in FIG. 8;

FIG. 10 is a bottom view of the pillow shown in FIGS. 8 and 9;

FIG. 11 is a front view of the pillow shown in FIGS. 8–10;

FIG. 12 is a rear view of the pillow shown in FIGS. 8–11;

FIG. 13 is a left side view of the pillow shown in FIGS. 8–12; and,

FIG. 14 is a right side view of the pillow shown in FIGS. 8–13.

The boundary of the claimed design is at the end of the solid lines and formed by the dot-dot-dash broken lines. All other broken lines form environmental structure and form no part of the claimed portion of the design.
